DESIGN FOR A CRIB TOY

Elmer Szantay, Chicago, Ill., assignor to Sandee Manufacturing Company

Application March 24, 1948, Serial No. 145,320

Term of patent 14 years

(Cl. D34—15)

To all whom it may concern:

Be it known that I, Elmer Szantay, a citizen of the United States, residing at Chicago, county of Cook, and State of Illinois, have invented a new, original, and ornamental Design for Crib Toy, of which the following is a specification, reference being had to the accompanying drawing, forming a part thereof, in which:

Fig. 1 is a plan view of the crib toy, showing my new design;

Fig. 2 is a side elevational view thereof; and
Fig. 3 is an end elevational view thereof.

I claim:

The ornamental design for a crib toy, as shown.
ELMER SZANTAY.
